UNITED STATES PATENT OFFICE

111,509

DESIGN FOR A SHOE

Herman B. Delman, New York, N. Y.

Application August 15, 1938, Serial No. 79,339

Term of patent 3½ years

To all whom it may concern:

Be it known that Herman B. Delman, a citizen of the United States and resident of New York city, in the county of New York and State of New York, has invented a new, original, and ornamental Design for a Shoe, of which the following is a specification, reference being had to the accompanying drawing, forming part thereof, in which,

Fig. 1 is a plan view and Fig. 2 is a perspective view of a shoe, showing my new design.

I claim:

The ornamental design for a shoe, as shown.

HERMAN B. DELMAN.
